LABEL DISPENSER

Carl A. Flood, Framingham, Mass., assignor to
 Dennison Manufacturing Company, Framingham,
 Mass., a corporation of Massachusetts

Application January 2, 1941, Serial No. 372,862

11 Claims. (Cl. 242—55.2)

This invention relates to devices for dispensing labels which are adhesively mounted on one side of an elongate backing strip and more particularly to labels having normally tacky adhesive which readily peels off the backing sheet.

Objects of the present invention are to provide improved dispensing devices which are simple and economical in construction, which are efficient and reliable in use, which are easy to load, which facilitate the separation of the labels from the backing strip and which are generally superior to prior devices of the type referred to.

In one aspect the invention involves the use of a label strip having the backing split longitudinally into two (or more) ribbons, the labels being removed from the backing by first peeling back one ribbon to uncover a portion of each label successively and subsequently separating the labels from the other ribbon, preferably by individually peeling each partially uncovered label from the other ribbon while holding the other ribbon on opposite sides of the label to counteract the pull on the ribbon while the label is being peeled off. The preferred way of holding the second ribbon while a label is being peeled off consists in drawing the ribbon taut over a convex surface which engages only the one remaining ribbon, thereby more effectively to hold the ribbon in predetermined position while the label is being peeled off. The surface may be stationary or it may be in the form of a drum (wheel or roller) which moves with the strip.

In another aspect the ribbons are pulled from the label material with the line of separation between one ribbon and the label material offset lengthwise of the strip from the location where the other ribbon and label material are separated. This is preferably accomplished by feeding the label strip lengthwise along a predetermined path, peeling one ribbon from the strip at one location along the path and at another location farther along the path separating the labels from the other ribbon either by peeling the labels from the ribbon or vice versa. In the preferred embodiment the first ribbon is fed along a branch path back into edge to edge relationship with the second ribbon so that the two ribbons may be fed conjointly into the waste compartment.

For the purpose of illustration typical embodiments of the invention are shown in the accompanying drawings in which

Fig. 1 is a top plan view;

Fig. 2 is a top plan view of a part of the device;

Fig. 3 is a section on line 3—3 of Fig. 1;

Fig. 4 is a section on line 4—4 of Fig. 3;

Fig. 5 is a section on line 5—5 of Fig. 1;
 Fig. 6 is a section on line 6—6 of Fig. 1;
 Fig. 7 is a plan view of a second embodiment;
 Fig. 8 is a side elevation of the second embodiment, showing one of the labels in section and one partially peeled from the second ribbon;
 Fig. 9 is a side elevation viewed from the left of Fig. 7; and

Fig. 10 is a side elevation of a modification.

The particular embodiment of the invention shown in Figs. 1 to 6 comprises a base 1 and a cover 2 hinged to the base at 3, the parts preferably being molded with Bakelite or the like. The base 1 is provided with partitions 4 and 5 which divide the interior of the base into three compartments 6, 6' and 7. The cover 2 is also provided with a partition 8. The curved ends and the partition 8 extend down to the plane 9 (Fig. 3) but the cover has no sides. The sides of the base extend above the level 9 to close the open sides of the cover when the cover is closed (Fig. 4) but the partitions 4 and 5 terminate at the level 9.

As shown in Figs. 1, 3 and 4 the label strip comprises a backing divided longitudinally by a cut C into two ribbons B and B', the labels L being approximately rectangular in outline and being mounted end to end on the backing. As shown in Fig. 3 the roll R of the label material is dropped loosely into compartment 6 and the free end is threaded through the cover with the two backing ribbons projecting downwardly into the waste compartment 7 between the feed roller 11 and the pressure roller 12. The guideway for the label strip intermediate the supply compartment 6 and the rollers comprises a vertical passageway defined by the wall 13 and the pressure shoe 14 and an oval shaped guide comprising upper and lower portions 16 and 17 projecting laterally from the vertical portion 18. As shown in Fig. 4 the width of the upper portion 16 is approximately equal to that of one of the backing ribbons and the width of the lower guide 17 is approximately equal to that of the entire label strip. Extending lengthwise of the lower guide 17 approximately at the middle thereof is a shoulder 19 to serve as a guide for the edge of the ribbon B. A corresponding edge guide is provided on the other guide 16 by extending the wall 18 slightly above guide 16 as indicated at 21. At the upper end of the vertical wall 13 is an edge 22 over which the backing ribbon B is peeled away from the labels and thence passes along the lower surface of the lower guide 17. The other ribbon B' continues upwardly over the

guide 16 with the uncovered portions of the labels projecting beyond the guide 16 as indicated in Fig. 4. At any point along the upper guide 16 each label may be peeled individually from the second ribbon B' by grasping the projecting half of the label. As the label is peeled away from the ribbon B' the ribbon is prevented from following the label by holding the ribbon taut over the convex guide 16 by the friction shoe 14 which presses the label strip against the wall 13 in response to the spring 24, the shoe 14 having a handle 26 projecting through an opening in the top of the cover with which the shoe may be conveniently retracted against the action of the spring for threading purposes.

After the two backing ribbons have been brought back into edge to edge relationship over the feed roller 11 they may be fed into the compartment 7 by rotating the roller 11 through the medium of the projecting handle 31, the side wall of the base being recessed at 30 (Figs. 1 and 5) to accommodate the handle. The feed roller 11 rotates on a stud 32 fast in the cover 2 (Fig. 5). The pressure roller 12 rotates on a stud 33 fast to an arm 34 which in turn is fast to a stud 36 rotatably mounted in the cover 2 (Fig. 6). Inasmuch as the stud 33 is out of alignment with the stud 36 rotation of the arm 34 about the axis of the stud 36 causes the roller 12 to swing toward and from the feed roller 11. A spring 31 seating in a recess 38 in the arm 34 normally urges the pressure roller 12 toward the feed roller 11 to pinch the backing ribbons therebetween. The pressure roller 12 may be retracted for threading purposes by means of the lower end of the arm 34 which projects somewhat below the lower edge of the cover (Fig. 3).

To prevent the backing ribbons B and B' from sticking to the roller 11 or the roller 12 instead of feeding downwardly therebetween, a stripping plate 41 (Fig. 2) is secured to the bottom of the cover by means of screws 42 (Fig. 5) extending through openings 43 in the plate. The plate is provided with a recess into which two pairs of stripping fingers 44 and 46 project from opposite sides. The fingers 44 project from the left (Figs. 1 and 3) into grooves 47 in the pressure roller 12 and the fingers 46 project from the right into the grooves 48 in the feed roller 11. These stripping fingers not only prevent the backing ribbon from winding around the rollers but they prevent the rollers from slipping off their studs 32 and 33. Mounted on one end of the stripping plate 41 is a spring detent 49 whose upper free end engages the serrations 50 (Fig. 4) on the periphery of the feed roller 11 to prevent retrograde movement of the rollers in response to the pulling action of the labels as they are peeled from the second backing ribbon B'.

To load the device shown in Figs. 1 to 6 the cover is opened, a roller R of label material is dropped into the compartment 6, the ribbons are peeled back from the foremost labels sufficiently to permit the ribbons to be threaded through the cover and thence between the rollers as shown in Fig. 3. Inasmuch as the space between the guide 13 and the shoe 14 is open on the outside when the cover is lifted the label strip may be threaded into this space edgewise of the strip after the shoe 14 is retracted as aforesaid. Likewise the ribbons B and B' may be slipped in between the feed rollers from the left (Fig. 4) edgewise of the ribbons after retracting the pressure roller as aforesaid. In use the two backing ribbons are conjointly fed forward along their respective

paths by means of the handle 31 until one or more labels project from the upper guide 16 as illustrated in Fig. 4. After all of these projecting labels have been peeled off the ribbons are again advanced until one or more labels are again presented for use.

The modification shown in Fig. 10 is similar to that shown in Figs. 1 to 8, corresponding parts being correspondingly numbered. However it differs in that the peeling edge 22' for the outside ribbon is located near the end of the narrow ledge 16' instead of the beginning of the ledge. Thus the ledge 16' is full width throughout almost its entire length so that it serves as a solid backing for writing on the labels throughout the entire width of the labels.

The embodiment shown in Figs. 7, 8 and 9 comprises a base 52 having an extension 53 upon which a roll R of label material is rotatably mounted by means of a stud 54. Fastened to the base by means of two screws 56 is a cylindrical post 57 having in its upper end a groove 58 extending down to the level 59 (Fig. 8). Journaled on the lower end of the cylindrical post is a drum having a hub 61, a peripheral flange 62, whose width is approximately equal to that of the backing ribbon B', and a knurled portion 63 of slightly greater diameter to provide a shoulder 64 for one edge of the ribbon B' on the flange 62. Mounted on top of the post 57 by means of screws 66 are two plates 67 and 68. On the outer end of the plate 67 a roller 71 is journaled by means of a stud 72. The outer end of the plate 68 not only carries a corresponding roller 73 journaled on stud 74 but it also carries a gear wheel 78 meshing with gears 78 and 79 fast to the drum 61 and roller 73 respectively. The peripheral surface of the roller 73 is preferably covered with friction material 81 such as a rubber coating. Opposite the roller 73 is a pressure roller 83 journaled on an arm 84 which is pivoted to the base at 85 and urged toward the roller 73 by means of spring 86, the pressure roller also overlapping the flange 62 of the drum as shown in Fig. 8.

At the left-hand side of the base 52 a block 87 is pivotally mounted on the base by means of an upstanding stud 88, the block being somewhat wider than the label strip comprising the two backing ribbons B and B' and the circular labels 50. The portion of the block opposite the label strip extends to the line 91 (Fig. 9) but the portion overlapping the knurled flange 63 of the drum terminates at the line 92. Mounted on the inner face of the block by means of the screws 93 is a plate 94 having a curved rearward end and a forward end which terminates at the line 95 on the side opposite ribbon B and at the line 92 on the side opposite ribbon B'. The inner face of the block 87 is recessed throughout the width of the label strip to provide a passageway for the strip between the block and the plate 94. A spring 96 holds the block 87 in the position shown in Fig. 7.

To load the device the end of the roll R is threaded between the block and the plate 94, the upper backing ribbon B is then peeled away from the labels throughout a sufficient distance to fold it back over the edge 95 of the plate 94, and then thread it over the roll 71, through the groove 58 between the rolls 73 and 83 and thence through the opening 97 in the base to a suitable waste receiver. The other backing ribbon B' is wound around substantially half the periphery of the drum, thence passes under the roller 83 in edge to edge relation with the ribbon B and then passes

through the opening 87. In operation the drum is rotated in the direction of the arrow by engagement with the knurled periphery 63 to present the labels in the position shown in Figs. 7 and 8 where the upper portions of the labels may be grasped between the thumb and finger and readily peeled off the ribbon B'. While the labels are being peeled off, the ribbon B' is held taut against the flange 62 of the drum by virtue of the frictional engagement of the forward edge 88 of the block 87 against the ribbon B' on the drum, the spring 96 being adjusted to produce sufficient friction for this purpose.

It should be understood that the present disclosure is for the purpose of illustration only and that this invention includes all modifications and equivalents which fall within the scope of the appended claims.

I claim:

1. In dispensing labels from a strip having the labels adhesively mounted in a row on a backing which is divided longitudinally into two ribbons, the method of dispensing the labels which comprises drawing the strip over a convex surface which engages only one ribbon, peeling the other ribbon from the strip to uncover a portion of at least one label opposite the convex surface and, while the first ribbon is drawn over the surface, peeling said label away from it by grasping said uncovered portion opposite one edge of said convex surface.

2. In dispensing labels from a strip having the labels adhesively mounted in a row on a backing strip which is divided longitudinally into two ribbons, the method of dispensing the labels which comprises feeding the strip lengthwise along a predetermined path having a portion curved longitudinally of the path with the labels on the convex side of the curved portion, peeling one ribbon from the strip at one location along the path to uncover a part of the adhesive side of each label as it passes that location and at another location farther along said path in said curved portion peeling the labels from the other ribbon while holding the other ribbon in its curved condition to counteract the pull on the ribbon while the labels are being peeled off.

3. In dispensing labels from a strip having the labels mounted in a row on a backing which is divided longitudinally into two ribbons disposed edge to edge, the method of dispensing the labels which comprises feeding the strip along a main path, peeling one of the ribbons from the labels at one location along said path to uncover the adhesive sides of portions of the labels and thence feeding the ribbon along a branch path back into edge to edge relationship with the other ribbon at another location in the main path, and holding the second ribbon taut between said locations while the labels are peeled therefrom by grasping said uncovered portions.

4. For dispensing labels from a strip having the labels mounted in a row on a backing which is divided longitudinally into two ribbons, a device having a path along which the strip is fed, means for peeling one ribbon from the labels at one location along said path to uncover the adhesive sides of portions of the labels, and means for holding the second ribbon while the labels are peeled therefrom by grasping said uncovered portions, said holding means being located in advance of the location where the labels are peeled from the second ribbon, said holding means including a surface extending across the back of one ribbon and terminating near the

line of division between the two ribbons so as not to contact the tacky surface of the labels after they are separated from the other ribbon.

5. For dispensing labels from a strip having the labels mounted in a row on a backing which is divided longitudinally into two ribbons, a device having a path along which the strip is fed, means for peeling one ribbon from the labels at one location along said path to uncover the adhesive sides of portions of the labels, and tensioning means for holding the second ribbon taut while the labels are peeled therefrom by grasping said uncovered portions, said tensioning means being located in advance of the location, where the labels are peeled from the second ribbon, said tensioning means including a surface extending across the back of one ribbon and terminating near the line of division between the two ribbons so as not to contact the tacky surface of the labels after they are separated from the other ribbon.

6. For dispensing labels from a strip having the labels mounted in a row on a backing which is divided longitudinally into two ribbons, a device having a path along which the strip is fed, means for peeling one ribbon from the labels at one location along said path to uncover the adhesive sides of portions of the labels, a support extending along the path beyond said location to engage the other ribbon with said portions of the labels projecting edgewise from the support, and means for holding the second ribbon against said support while the labels are peeled therefrom by grasping said projecting portions, said support and holding means being arranged to hold said portions spaced from the device so that they may be freely grasped between the two surfaces while projecting from the support as aforesaid.

7. For dispensing labels from a strip having the labels mounted in a row on a backing which is divided longitudinally into two ribbons, a device having a path along which the strip is fed, means for peeling one ribbon from the labels at one location along said path to uncover the adhesive sides of portions of the labels, a convex support extending along the path beyond said location to engage the other ribbon with said portions of the labels projecting edgewise from the support, and means for holding the second ribbon taut over said convex support while the labels are peeled therefrom by grasping said projecting portions, said holding means being located in advance of the location where the labels are peeled from the second ribbon.

8. For dispensing labels from a strip having the labels mounted in a row on a backing which is divided longitudinally into two ribbons, a device having a path along which the strip is fed, means for peeling one ribbon from the labels at one location along said path to uncover the adhesive sides of portions of the labels, a support extending along the path beyond said location to engage the other ribbon with said portions of the labels projecting edgewise from the support, the support being convex lengthwise of said path, and means for holding the second ribbon taut over said convex support while the labels are peeled therefrom by grasping said projecting portions, said holding means being located in advance of the location where the labels are peeled from the second ribbon.

9. For dispensing labels from a strip having the labels mounted in a row on a backing which is divided longitudinally into two ribbons dis-

posed edge to edge, a device having a main path along which the strip is fed, means for peeling one of the ribbons from the labels at one location along said path to uncover the adhesive sides of portions of the labels and thence feeding the ribbon along a branch path back into edge to edge relationship with the other ribbon at another location in the main path, and means for holding the second ribbon taut between said locations while the labels are peeled therefrom by grasping said uncovered portions, said holding means including a surface extending across the back of one ribbon and terminating near the line of division between the two ribbons so as not to contact the tacky surface of the labels after they are separated from the other ribbon.

10. For dispensing labels from a strip having the labels mounted in a row on a backing which is divided longitudinally into two ribbons, a device having a path along which the strip is fed, means for peeling one ribbon from the labels at one location along said path to uncover the adhesive sides of portions of the labels, a drum

5 over which the strip feeds from said location with the other ribbon engaging the periphery of the drum and with said portions of the labels projecting edgewise of the strip from the drum, and means for holding the second ribbon against the drum while the labels are peeled therefrom by grasping said projecting portions.

15 10. For dispensing labels from a strip having the labels mounted in a row on a backing which is divided longitudinally into two ribbons, a device having a path along which the strip is fed, means for peeling one ribbon from the labels at one location along said path to uncover the adhesive sides of portions of the labels, a drum over which the strip feeds from said location with the other ribbon engaging the periphery of the drum and with said portions of the labels projecting edgewise of the strip from the drum, and a spring-pressed roller for holding the second ribbon against the drum while the labels are peeled therefrom by grasping said projection portions.

CARL A. FLOOD.
